Des. 183,551
Patented Sept. 16, 1958

183,551

MARBLE RUNWAY GAME APPARATUS

Stephen F. Williams, Jr., Rochester, N. Y.

Application March 26, 1957, Serial No. 45,441

Term of patent 14 years

(Cl. D34—15)

Fig. 1 is a top plan view of a marble runway game apparatus, showing my new design;

Fig. 2 is a side elevational view;

Fig. 3 is an end elevational view; and

Fig. 4 is a fragmentary cross-sectional view thereof, taken on line 4—4 in Fig. 1.

I claim:

The ornamental design for a marble runway game apparatus, substantially as shown.
